ALARM DEVICE

Thomas W. Moody, Houston, Tex.

Application June 4, 1934, Serial No. 728,942

4 Claims. (Cl. 116—87)

This invention relates to an alarm device.

An object of the invention is to provide a device of the character described specially adapted to be installed at or adjacent a wall opening such as a window opening, and equipped with a blank cartridge and means for exploding the charge in case of an unauthorized interference with the closure of the opening.

Another object of the invention is to provide an alarm device adapted to be attached to a window casing adjacent the screen of the window and having means operative to explode upon the opening or partial opening of the screen.

The device is primarily intended to give a warning in case of an attempted burglary through a window or other opening of a building.

A further object of the invention is to provide an alarm device which is of very compact structure which may be readily installed, and removed, and which is inconspicuous in appearance.

A further object of the invention is to provide an alarm device that may be readily locked in inactive position.

With the above and other objects in view, the invention has particular relation to certain novel features of construction, operation and arrangement of parts, an example of which is given in this specification and illustrated in the accompanying drawing, wherein:

Figure 1 shows a horizontal sectional view, taken through a window opening and showing the alarm device installed.

Figure 2 shows a side elevation of the device.

Figure 3 shows a side elevation partly in vertical section.

Figure 4 shows a vertical sectional view of the device in its relation to the window screen and shown in active position.

Figure 5 shows a side view of the device partly in vertical section in firing position.

Figure 6 shows a transverse sectional view taken on the line 6—6 of Figure 2, and

Figure 7 shows a front elevation of a window frame and screen showing the alarm device assembled therewith in dotted lines.

In the drawing, the numerals 1, 1 designate the side members of a window frame showing the upper sash 2 vertically slidable in said frame.

The numeral 3 designates the window screen as a whole which is secured in the usual manner to the outer side of the window frame so as to protect the window. The screen will usually be swung from the top, as is the common practice, so that its lower end may be swung outwardly.

Secured to one side of the window casing and spaced between the upper sash and the screen frame there is a metal housing 4, preferably square in horizontal cross section. This housing may be secured in place by screws as 5, 6, the latter of which is inaccessible when the firing mechanism hereinafter described is installed therein. Opposite the screw 6 the housing 4 has an opening 7 for access to the screw by a screwdriver for installing said housing. 10

The housing 4 has a transverse web 8 having an upturned annular flange 9 forming a bearing for the blank cartridge 10. The rim 11 of the cartridge has a greater diameter than that of the bearing so that the said rim will engage the flange 9. Beneath the web 8, the side of the housing 4 adjacent the window screen is open and secured to the screen frame and projecting through said open side into the housing there is a retainer 12 which is secured to the screen frame by means of a screw 13. When the alarm device is in active position the lower end of the cartridge 10 engages the retainer 12 to hold the cartridge rim elevated above the flange 9.

Within the housing 4 there is a cylinder 14 whose outer end is closed. Within this cylinder there is a plunger 15 whose lower end terminates in a firing pin 16 aligned with the cap of the cartridge. A coil spring 17 is interposed between the closed end of the cylinder and the plunger 15 and the upper end of said plunger has a reduced stem 18, which is surrounded by the spring 17.

One side of the housing 4 above the web 8 has a side opening 19 through which the cartridge 10 may be inserted into said bearing before the cylinder 14 is inserted into the housing. Said cylinder with the plunger and spring assembled therein may then be inserted downwardly into the housing until the firing pin 16 engages the cap of the cartridge. Said cartridge will be supported on the retainer 12 and as the cylinder is forced downwardly into place, the spring 17 will be placed under compression. The cylinder has a lateral projection 20 and as the cylinder is forced into position it should be turned so that this projection will pass down the corner 4' of the housing 4 until the projection clears the upper end of the opening 19 and should then be turned by the handle 21 until the projection 20 engages underneath the inside diagonal stop 22 across another corner of the housing 4 and this will maintain the compression on the spring 17. 50

In case of an attempted burglary, should the burglar attempt to open the screen by pulling the 55

lower end thereof outwardly, the side of the screen frame carrying the retainer 12 will move outwardly from the window casing the other side of the screen frame being retained by the stop 23 which is secured to the adjacent side of the window casing. When the screen is pulled outwardly as shown in Figure 5 and the retainer 12 releases the lower end of the cartridge 10, said cartridge will be suddenly projected downwardly by the spring 17 until its rim 11 hangs on the flange 9 whereby the cartridge will be suddenly stopped and impact of the firing pin against the cartridge cap will ignite the explosive charge whereby an alarm will be given.

15 If it be desired to render the alarm device inactive, the cylinder 14 may be turned by the handle 21 a quarter of a turn, the projection 20 passing around through the upper portion of the opening 19 until said projection clears said opening and moves into the adjacent corner of the housing and said cylinder will then be moved outwardly by the spring 17 relieving the compression on said spring.

25 The drawing and description disclose what is now considered to be a preferred form of the invention by way of illustration only, while the broad principle of the invention will be defined by the appended claims.

What I claim is:

30 1. An alarm device comprising a housing, a displaceable retainer associated therewith, a cartridge supported on the retainer, a stop for the cartridge, means including a firing pin acting yieldingly against the cartridge and effective to

project the cartridge against the stop and to fire the cartridge upon displacement of the retainer.

2. An alarm device comprising a housing, a cartridge mounted therein, a displaceable retainer for the cartridge, a stop against which the cartridge is engageable upon displacement of the retainer, a cylinder in the housing, a plunger in the cylinder having a firing pin engageable against the cap of the cartridge, and a yieldable member acting against the plunger.

3. The combination with a closure for a wall opening, of an alarm device containing an explosive cartridge and a firing mechanism therefor, means on the closure normally supporting the cartridge to hold the cartridge and firing mechanism in retracted position, said means being movable, upon movement of the closure toward open position, to release the cartridge and to permit it to move to firing position, and means for arresting such cartridge movement.

4. An alarm device comprising a housing, a bearing therein, a cartridge in the bearing, a stop to limit the movement of the cartridge in the bearing, a plunger having a firing pin aligned with the cap of the cartridge, a yieldable member normally acting against the plunger, means movable into one position to maintain the cartridge in one position and to maintain said yieldable member inactive and movable into another position to release the cartridge to render the yieldable member active to allow the movement of the cartridge into firing position against the stop.

THOMAS W. MOODY.
